UNITED STATES PATENT OFFICE.

GEORGE A. SMITH AND DENIS SMITH, OF ONTARIO, CALIFORNIA.

ORCHARD HEATER.

Application filed March 18, 1925. Serial No. 16,410.

This invention relates to orchard heaters and is more particularly directed to an orchard heater in which the fuel is completely burned so as to eliminate smoke commonly formed by such heaters and to obtain a maximum heating value from the fuel used.

An object of this invention is to provide an orchard heater of simple and inexpensive construction and easy to operate and place 10 in the proper position for use, and when so positioned and in use, will distribute the heat over the surface of the ground and further will act to heat the ground so as to obtain a maximum heating efficiency from 15 the fuel consumed.

An object of this invention is to provide an apparatus for the combustion of the vapors formed from an ordinary smudge pot in which means are provided for thoroughly 20 mixing the vapors formed with sufficient quantity of air to insure the complete combustion of the vapors so as to obtain the maximum heating value from the fuel consumed and which apparatus is of simple 25 and inexpensive construction.

Other objects and advantages of this invention will be apparent from the following detailed description of a preferred embodiment thereof as illustrated in the accompanying drawings.

In the drawings:

Fig. 1 is a side elevation of an orchard heater assembly embodying this invention.

Fig. 2 is a central sectional side elevation 35 of the orchard heater embodying this invention.

Fig. 3 is a sectional end elevation thereof taken substantially on the line 3—3 of Fig. 2.

40 In the preferred form of this invention shown in the accompanying drawings, 1 illustrates a smudge pot of any suitable construction, as is well understood in the art. From a stack 2 of the smudge pot a conduit 3 conveys vapors of the fuel into a vapor collecting chamber 4 which vapor collecting chamber 4 is separated from a combustion chamber 5 by means of a vertical plate partition 6. The fuel employed in the 45 smudge pot is usually what is known as slop distillate. The conduit 3 may be formed of any suitable material, and it has been found that the same may be constructed efficiently from a plurality of sections of stove pipe material, and the same telescopes over the pipe section 7 which is

affixed to the body 8 of the orchard heater in any suitable manner such as illustrated at 9.

The vapors leaving the smudge pot are 60 collected in the chamber 4 and means are provided for thoroughly mixing these vapors with air as the same are introduced into combustion chamber 5 so that a complete combustion will be effected and the 65 maximum heat obtained therefrom which means preferably comprise the plate partition 6 which is secured to the body 8 by any suitable means such as are illustrated at 10 and the plate 6 is secured to the body 8 at 70 a position slightly in the rear of the air admitting slots 11 formed in the body 8.

The perimeter of the plate 6 is cut away as illustrated in Fig. 3 to form a plurality of ports 12 when the same is secured in position within the body 8 so that the vapors leaving the vapor collecting chamber 4 pass through the ports 12 and are directed into the stream of air admitted through the ports 11, whereby the air and the vapors are 80 thoroughly commingled so that a complete combustion of the vapors is effected in the chamber 5. There being no bottom secured to the body 8 of this orchard heater, the flames are burning directly over the ground 85 and heat the same for a considerable distance around the heater which increases the radiating surface of the orchard heater and adds greatly to the efficiency of this orchard heater in maintaining the orchard 90 trees free from frost.

A stack 13 is secured to the body 8 as illustrated at 14 to carry away the combustion products formed in the chamber 5, the stack 13 extending upward from this orchard heater any desired distance, preferably such a distance as to insure at all times the complete combustion of the vapors admitted into the chamber 5 and so that the heat of this combustion will be radiated to 100 a maximum degree by the walls of the combustion chamber and the stack 13 and will not pass directly up from the top of the stack 13.

The body 8 of this orchard heater is preferably formed of sheet metal and is, therefore, of inexpensive construction. The sheet metal forming this body 8 is lapped over, as illustrated at 15 to reinforce the body of the orchard heater.

105 It will be apparent from the foregoing that we have provided a simple and inex-

pensive orchard heater by the means of which a complete combustion of the fuel used is obtained and a maximum heat radiating or directing power is obtained from the fuel.

Having fully described a preferred embodiment of this invention, it is understood that we do not wish to be limited to the exact construction herein set forth, which may, 10 obviously, be varied in detail without departing from the spirit of the invention, as set forth in the appended claims.

We claim:

1. In an orchard heater, the combination 15 of an oil vaporizing member, a vapor collecting chamber, means for conducting the vapors from the oil vaporizing member to the vapor collecting chamber, a combustion chamber separated from the vapor collecting 20 chamber by a plate, a slot formed in the combustion chamber at the entrance end thereof at a point advanced from the plate, and a plurality of ports formed in the plate for directing the vapors into the air admitted 25 through the said slot.

2. In an orchard heater, the combination 30 of a vapor collecting chamber, a combustion chamber separated from the vapor collecting chamber by a plate, a slot formed in the combustion chamber at the entrance end thereof and at a point to the rear of the plate, and a plurality of ports formed along the perimeter of the plate for directing the vapor into the air admitted through the slot.

3. In an orchard heater, the combination 35 of a body, a vapor collecting chamber within the body, a combustion chamber within the body and separated from the vapor col-

lecting chamber by a plate, means for admitting air into the combustion chamber at 40 the entrance end thereof, and a plurality of ports formed in the plate for directing the vapors into the air admitted.

4. In an orchard heater, the combination 45 of a vapor collecting chamber, a combustion chamber separated from the vapor collecting chamber by a plate, means for securing the said plate in position so as to permit the vapor to pass from the vapor collecting chamber to the combustion chamber, a slot 50 formed in the combustion chamber at the entrance thereof and at a point at the rear of the plate so that the incoming air is directed into the vapor admitted around the said plate into the said combustion chamber.

5. In an orchard heater, the combination 55 of an oil vaporizing member, a vapor collecting chamber, means for conducting the vapors from the oil vaporizing member to the vapor collecting chamber, a combustion 60 chamber, a plate separating the combustion chamber from the vapor collecting chamber, means holding the said plate in position and spaced from the wall of the said chamber so as to permit the flow of vapor from the vapor collecting chamber into the said combustion chamber, and a slot formed in the combustion chamber at the entrance end thereof at a point advanced from the said 65 plate for directing the air into the vapors admitted around the said plate into the combustion chamber.

Signed at Ontario, California, this 9th day of March, 1925.

GEORGE A. SMITH.
DENIS SMITH.
